UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 14,870, dated March 11, 1884.

Application filed January 28, 1884. Term of patent 3½ years.

To all whom it may concern:

Be it known that I, OTTO HEINIGKE, of New Utrecht, in the State of New York, have invented a new and original Design for Carpets, 5 of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

15 The design consists of a number of irregular and variously-shaped panels covering the entire face of the design.

The feature of the design is the irregular lobular outlines of these panels. The ground of the different panels is of contrasted ornamentation, and the flower and leaf groups on the different panels are independent groups in each instance, all as clearly shown in the accompanying photograph. 20

I claim—

The design for a carpet, substantially as shown and described. 25

OTTO HEINIGKE.
